(57) **CLAIM**

The ornamental design for an in-store marketing sign, as shown and described.

DESCRIPTION

FIG. 1 is a front view of an in-store marketing sign;

FIG. 2 is a left side view thereof;

FIG. 3 is a right side view thereof;

FIG. 4 is a back view thereof;

FIG. 5 is a top view thereof; and,

FIG. 6 is a bottom view thereof.

The dash-dot-dash lines shown in the drawings are included for purposes of illustrating portions of the in-store marketing sign and form no part of the claimed design. The dotted lines shown in the drawings represent scores that do form part of the claimed design for the in-store marketing sign. The solid interior vertical and horizontal lines in FIGS. 1 and 4 represent through cuts that do form part of the claimed design for the in-store marketing sign.
